(57) CLAIM

The ornamental design for a fruit and vegetable holder, as shown, and described.

DESCRIPTION

FIG. 1 is a perspective view of a fruit and vegetable holder, showing our new design;

FIG. 2 is a perspective view thereof with alternate unclaimed ornamentation;

FIG. 3 is a perspective view thereof with alternate unclaimed ornamentation;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is a perspective view thereof in an open position. The broken lines in the drawings depict portions of the fruit and vegetable holder that form no part of the claimed design.
